UNITED STATES PATENT OFFICE.

WILLIAM T. GLASS, OF NAPANOCH, NEW YORK, ASSIGNOR OF ONE-HALF TO
ANTHONY D. HUNGERFORD, OF NAPANOCH, NEW YORK.

DOOR-OPERATING MEANS.

No. 851,592.

Specification of Letters Patent.

Patented April 23, 1907.

Application filed June 13, 1906. Serial No. 321,473.

To all whom it may concern:

Be it known that I, WILLIAM T. GLASS, a citizen of the United States of America, residing at Napanoch, in the county of Ulster and State of New York, have invented new and useful Improvements in Door-Operating Means, of which the following is a specification.

This invention relates to improvements in sliding doors for railway cars, barns, carriage houses, shops and other structures.

One object of the invention is to provide a door of this type which when unlocked may be easily adjusted, but which when locked will be held firmly and securely in locked position, and which may also be locked in any desired position in its range of movement.

Another object is to provide means for mounting and locking the door in such manner that when the locking mechanism is thrown into action the door will be fastened at top and bottom and tight against the door frame, so that it will be held firmly supported against all efforts to open it by unauthorized persons and will be wind and storm proof, and will also be sustained against any tendency to rattle under the action of wind currents or, when used upon a railway car, from rattling or vibrating under the motion of the car.

A further object of the invention is to provide improved locking means which is simple of construction, efficient in action, and may be readily and conveniently adjusted to lock the door.

With the above and other objects in view, the invention consists of the combination and arrangements of parts hereinafter more fully described and claimed, reference being had to the accompanying drawings, in which,—

Figure 1 is a view in elevation of a car or other structure equipped with my invention, showing the released door in partly open position. Fig. 2 is a similar view showing the door locked in closed position. Fig. 3 is a vertical section on the line 3—3 of Fig. 2. Fig. 4 is a detail section of one of the hangers.

Referring to the drawings, the numeral 1 designates the frame of a car or other structure, provided with a doorway 2 having at its outer side a vertical buffer or stop rail 3 to limit the closing movement of the door. Beyond the other side of the doorway is a simi-

lar buffer or stop rail 4 which limits the opening movement of the door, and extending between these buffers are upper and lower rails 5 and 6, which are respectively provided with upper and lower sets of locking teeth 7 and 8.

The door 9 is arranged to slide between the rails and extends at its lower edge on the inside of the lower rail 6 which is arranged to form a guide passage between it and the wall of the car or structure. The said rail 6 is carried by a supporting plate 10, to the upper edge of which it is fastened in any preferred manner. The plate 10, which is preferably formed of sheet metal, is outwardly bowed or curved to form a guard or shield 11 below the lower edge of the door, and is secured at its lower edge at suitable intervals to spacing blocks 12 fixed to the wall of the structure. Said blocks space the said lower edge of the shield a sufficient distance from the wall to provide passages for the discharge of dirt and any other foreign matter which may gain access to the space between the shield and wall. The shield also acts as a guard to prevent ready access to the lower set of locking devices, as hereinafter described.

The door is supported at its upper end by hangers 13 which engage the rail 5 and hold the said upper end of the door from outward movement. Each hanger 13 is provided with a hooked portion 14 to take over the upper edge of the rail, said hooked portion being formed with a depressed locking projection 15 to coöperate with the teeth 7. Below the hook the hanger is provided with an oblique arm 16 extending upwardly and adapted to engage the rail to prevent the door from being forced upward to throw the hangers out of engagement with the rail 5. Between the hook and arm the hanger is inclined, as indicated at 17, in such a manner as to throw the upper edge of the door when elevated away from the wall of the structure and force the same when the door is lowered closely against the wall of the structure for a purpose herein-after described.

A rock shaft 18 is journaled in bearings 19 upon the lower portion of the door and is provided with crank portions 20 and 21. The crank portions 20 support bottom hangers 22 carrying rollers 23 to run upon the upper surface of the lower rail 6. The crank portions 21 have pivotally connected thereto locking

devices 24 provided at their lower ends with hooked portions 25 having teeth to engage the teeth 8 upon said rail 6. The crank shaft is also provided with an operating arm or lever 26, which is apertured at its upper end for the reception of a staple 27 on the door, to which staple an ordinary pad lock may be connected to hold the arms 26 and parts of the locking mechanism in locking position. The arm or lever 26 may also be provided with an apertured staple or projection 28 adapted to coöperate with a mortise lock 29 on the door. This lock may be of the type in which the bolt or locking mechanism thereof is both projected and retracted by a key, or it may be one of that type in which the locking bolt thereof will be automatically thrown into locking engagement with the staple 28 when the lever 26 is thrown up against the door to throw the door locking mechanism into action.

The construction and relative arrangement of the cranks, lower hangers 22 and locking devices 24 is such that when the lever 26 is thrown outwardly at right angles to the door, as shown in Fig. 1, the hangers 22 will hold the door slightly elevated with the upper hangers 13 thrown out of locking engagement with the teeth of the upper rail 5, the construction further being such that the hooked locking portions of the locking devices 28 in this position of the parts will lie below and out of engagement with the toothed surface 8 of the bottom rail 6, thus allowing the door to be freely moved in either direction on its supporting rollers 23. Upon shifting the lever 26 to the position shown in Fig. 2, the crank portions of the shaft will shift the lower hangers 22 and locking devices 24 in such manner as to allow the door to drop to a sufficient extent to bring the upper hangers 13 into locking engagement with the teeth of the upper rail 5, while drawing the locking portions of the locking devices 24 into locking engagement with the teeth of the lower rail 6, thus locking the door at top and bottom firmly in position. Upon the subsequent retraction of the lever 26, the door will be elevated and the parts reversely operated to release the top and bottom sets of locking devices, as will be readily understood. It will be observed that upon the retraction of the locking devices and elevation of the door the inclined surfaces 17 of the upper hangers 13 will force the door away from the wall of the structure, thus allowing the door to be freely moved back and forth, and that on the contrary when the locking mechanism is thrown into action and the door depressed, said inclined surfaces will force the door against the wall of the structure, so that it will be held in such firm engagement therewith as to be held solidly from rattling against the action of wind or vibrations, while at the same time rendering it practically impossible

for an unauthorized person to move the door to any extent by pressure or manipulation with any ordinary tools.

It will be understood from the foregoing description, taken in connection with the drawings, that by means of the locking mechanism the door may be securely fastened in any desired position in its range of movement, and that the action of the locking mechanism in holding the door firmly closed at top and bottom peculiarly adapts the door for use upon freight cars, barns and other out buildings in which a firmly locked door is a desideratum to prevent the entrance of wind and rain and tramps and other unauthorized persons.

By the use of the spring lock to hold the lever arm 26 in locking position, a high degree of safety is insured in the use of the door upon freight cars, as the locking mechanism cannot be thrown into action without it being held in locking position by the lock 29 on the door. Thus if a person in charge of the work in closing the car fails to lock the lever 26 visual evidence of that fact will be given, as the lever will not remain in locked position. Where a spring lock is employed, the key thereof may be transmitted with the weigh bill from the shipping to the destination point by mail or any other manner to prevent possible surreptitious release of the locking mechanism and opening the door. A seal of ordinary construction, such as used on car doors, may be applied to the staple 27 in conjunction with a padlock to give additional security.

It will be observed that as the door when locked will be held on opposite sides of its center at top and bottom, all tendency of its movement under pressure in any direction will be prevented, thus firmly locking it and supporting it in closed position.

Having thus described the invention, what is claimed as new, is:—

1. The combination with a car or other structure having a doorway, of toothed rails at the top and bottom of the doorway, a sliding door, hangers upon the top of the door engaging the upper rail and provided with locking portions to engage the toothed portion of said rail, rollers upon the lower end of the door arranged to travel upon the lower rail, locking devices arranged to engage the toothed surface of the lower rail, and operating means for throwing the locking devices into and out of engagement with the lower rail, said means being adapted to simultaneously depress the door to throw the upper hangers into locking engagement with the upper rail.

2. The combination with a car or other structure having a doorway, of rails at the top and bottom of the doorway, a sliding door, locking hangers upon the top of the door engaging the upper rail, locking devices upon

- the bottom of the door to engage the lower rail, rollers upon the bottom of the door to travel upon the lower rail, a crank shaft controlling the action of said locking devices and 5 rollers, whereby the door may be raised and lowered and the upper and lower locking devices simultaneously thrown into and out of action, and means for fastening the crank shaft in locking position.
10. 3. The combination with a car or other structure having a doorway, of rails at the top and bottom of the doorway, the lower rail being provided on its lower edge with rack teeth, a shield guarding the toothed surface 15 of the lower rail, a rock shaft on the door provided with crank portions, rollers and locking devices supported by said shaft, said rollers being arranged to run upon the upper surface of the lower rail and the locking devices to be 20 thrown into and out of action with the toothed surface of said rail when the shaft is moved in one direction or the other, means upon the upper end of the door for supporting the same from the upper rail, and means for locking 25 the rock shaft in adjusted position.
4. The combination with a car or other structure having a doorway and upper and lower toothed rails at the top and bottom of the doorway, of a door provided with rollers 30 to run upon the lower rail, hangers upon the upper end of the door loosely embracing the
- upper rail and adapted to interlock therewith, said hangers being normally supported by the rollers out of locking engagement with the rail, locking devices at the bottom of the door to engage the lower rail, and means for shifting the rollers and locking devices to simultaneously lower the door and move the hangers and locking devices into respective engagement with the upper and lower rails. 35
5. The combination with a car or other structure having a doorway, of stationary locking devices at the top and bottom of the doorway, coöperating locking devices at the top and bottom of the door, the upper locking devices being adapted to move the door in and out upon a down movement thereof, said locking devices being thrown into and out of action by such a down movement of the door, and means for simultaneously throwing the lower locking devices on the door into and out of engagement with the lower stationary locking device and simultaneously moving the door up and down to correspondingly adjust the upper locking 40 devices thereon. 45
- In testimony whereof, I affix my signature in presence of two witnesses.
